DRYING FORM

Filed Jan. 26, 1929

INVENTOR

John F. McNamara

By George E. Mueller, Atty.

UNITED STATES PATENT OFFICE

JOHN F. McNAMARA, OF CHICAGO, ILLINOIS

DRYING FORM

Application filed January 26, 1929. Serial No. 335,330.

My invention relates in general to drying forms, and more in particular to improvements in drying forms for combination undergarments similar to the type of drying form shown in my co-pending application, Serial No. 317,759, filed November 7, 1928.

The principal object of my present invention is to provide a single unit drying form capable of being freely and quickly adjusted 10 to any size garment whatsoever.

Another object is to provide a drying form in which the size of the legs and arms can be automatically increased in accordance with the size of the body.

15 Another object is the provision of a drying form in which the sizes can be changed with unusual rapidity.

Other objects and features of the invention will be apparent from a detailed description 20 taken with the accompanying drawings wherein

Fig. 1 is an elevational view showing one form which my invention may take;

Fig. 2 is an irregular vertical sectional view taken along the line 2—2 of Fig. 1, and

Fig. 3 is a fragmentary sectional view taken along the line 3—3 of Fig. 1 looking upwardly.

Referring now to the drawings the form 30 comprises two main body portions 11 and 12 hinged at 13 and 14 respectively so as to be foldable. The upper portions 11a and 12a are provided with openings 16 and 17 for lightness and are supported by retaining arms 18 and 19. These arms are secured to 35 uprights 21 and 22 and are provided with a certain amount of spring tension so that normally they tend to hold the body members 11 and 12 in any position in which they are placed. In order to more surely hold the parts in proper position I provide slots 40 23—23 in the frame members and bolts and wing nuts 24 extend through apertures in the retaining members so that the assembled frame may be tightened in any position desired.

About the body portions are a pair of shoulder members 27 and 28 both slidable along a retaining member 29 which 50 mounts the top of a vertical shoulder sup-

porting a member 31. The two shoulder members are prevented from being withdrawn from the retaining member by a pin 32 which is rigidly secured across the member and extends through slots 33 carried by the shoulder members. In this way the two shoulder members may be drawn outwardly without being removed from the retaining member. At the same time the slots 34 provided in the two members receive wing nut and bolt 36 60 which may be tightened to secure the members in place.

As the drawings indicate a tongue and groove construction is employed between the member 31 and the members 21 and 22 so 65 that vertical sliding movement between these members is permitted. In order to control the length of the form the member 31 is slid upwardly and a nut and bolt 37 extending through the members 18 and engaging in a 70 slot 38 in the member 31 maintain the proper adjustment.

The portions of the form just described are in all material ways the same as in the original form. The arm members, however, are 75 arranged differently as will now be shown. An arm member 39 is secured to each side of the form, by means of a triangular end piece 39a which is adapted to be slid sideways into a corresponding slot in the member 27 or 28 80 as the case may be. Near the outward extremity of the arm member a cooperating lower member 41 is provided pivoted to the arm member at 42 and having its end adapted to engage in any one of a number of suitable slots 43 provided in the shoulder members. This provides an adjustment for the width 85 of the arms, the end of the pivoted member 41 being adapted to extend into any one of the slots or sockets 43 to obtain the proper width. 90

I also provide means for automatically controlling the width of the legs as will now be shown. To the lower end of the members 21 and 22 leg enlarging members 46 and 47 95 are provided, these members being pivoted to the lower ends of the uprights 21 and 22, and having their ends extending into suitable sockets 48 and 49 provided in the lower portion of the leg part of the frame 11b and 12b. With these members mounted in this way the 100

enlarging of the body portion automatically enlarges the leg portion to the proper size.

In order to increase the usefulness of the form I arrange to provide feet 51 and 52 on the form, readily removable therefrom, but adapted to be quickly placed in position for drying such article as hose or the like. A foot of proper size can be employed for the stocking, and then the form expanded the proper 5 distance to take care of the leg size. While any suitable character of attaching means may be provided between the foot and legs of 11b and 12b I prefer an arrangement such as indicated wherein an extension 51a or 15 52a as the case may be projects upwardly into suitable sockets in the bottom of the leg.

In the use of the form, the garment is pulled up over the legs and over the body and lastly the arm portions are placed in position. This is done by simply extending them 20 into the arms, placing the members 41 in such position as to fill out the arms, and then sliding the entire assembly bodily sideways to fit the triangular end portion 39a and the end 25 of the member 41 into the proper openings in the shoulder piece.

While I have described certain details of one particular embodiment of my invention it is obvious that I am not restricted to the particular form shown, but the invention is limited only by the scope of the appended claims.

What I claim as new and desire to protect by Letters Patent of the United States is:

1. In a drying form for union suits a two part frame member forming the body portion and leg portions the leg portions being pivoted to the body portions, a central frame for receiving and securing the body portion, and leg extensions having one end pivoted to said 30 central portion and engaging the lower leg portion whereby the width of the legs is automatically increased when the width of the body is increased.

2. In a drying form for union suits a body portion including shoulder portions having a plurality of sockets, and leg portions all disposed as a single connected form, and removable arm portions formed with dovetailed connecting members at the ends thereof and adapted to be moved sideways to engage into sockets on the shoulder portions to secure the arms to the form, the arm portion consisting of two parts, each part being pivoted to the other and one part having an end adapted to extend into any one of a number of said sockets provided in a shoulder portion whereby the width of the arms may be regulated.

3. In a drying form a pair of frame members including body and leg portions slidable with respect to each other to control the width, an intermediate frame member for receiving the body portions, leg extensions secured to the intermediate frame member 60 and having connection to the bottoms of the

leg portions, whereby the width of the leg portions is determined by the position of the body portions, a shoulder portion having a pair of shoulder members adjustable with respect to each other to control width and adjustable together to control the over all length of the body, and removable arm members disposed on the shoulder members and adjustable as to width.

4. The combination described in claim 3 70 wherein the arm portions consist of arm members having triangular like extensions at the ends thereof adapted to fit sideways into corresponding sockets in the shoulder portions, and lower extending members pivoted to the ends of the arms and adapted to have their free ends extended into any one of a plurality of openings in the ends of the shoulder portions.

5. In a drying form, a pair of body portions laterally adjustable with respect to each other, leg portions pivotally connected thereto to permit folding of the form, means for adjusting the width of the leg portions incidental to the adjustment of the body portions.

6. In a drying form, a pair of body portions laterally adjustable with respect to each other, leg portions pivotally secured to the body portions, a central frame portion, means for adjusting the width of the leg portions pivotally secured to the central frame portion, the pivots of the leg portions and of the adjusting means being at right angles to each other.

7. In a drying form, body portions adjustable for width, a shoulder portion adjustable in height above the body portions, means for adjusting the width of the shoulder portion independently of the width of the portions, and arms secured to the shoulder portion.

8. In a drying form, a central frame member, body portions adjustable laterally with respect thereto, a shoulder portion adjustable longitudinally with respect thereto, and arms carried by the shoulder portion and adjustable therewith independently of the adjustment of the body portion.

9. In a drying form, a pair of central frame members, a shoulder member having a portion slideable between said frame members to permit adjustment of the shoulder member, arms extending laterally from said frame members, body portions adjustably secured to said laterally extending arms, and leg portions carried by said body portions.

In witness whereof, I hereunto subscribe my name this 22nd day of January, 1929.

JOHN F. McNAMARA.
